UNITED STATES PATENT OFFICE

ADOLPH C. HANSEN, OF CHICAGO, ILLINOIS

TALKING MACHINE

Application filed August 1, 1928. Serial No. 296,711.

This invention relates to improvements in talking machines and more particularly to a device which may be attached to conventional talking machines to adapt same for reproducing, in successive order and at separate intervals of time, portions of a sound record.

The object of my invention is to produce a device which may be conveniently attached to conventional talking machines and which may be used for playing successively and at separate intervals of time, a plurality of selections or parts of the matter contained on one record; a device which may be manually or automatically put into operation; in which, after the operation has been started, a tone arm and needle will be automatically lowered into operative relation to the record, but not until sufficient time has elapsed for the turn table carrying the record to have gained proper momentum so that, as soon as the needle contacts with the record, that part of the record to be played will be efficiently reproduced; and in which, after the needle has traversed a predetermined portion of the record, brake mechanism will be automatically actuated to stop the rotation of the turn table and record and, simultaneously or almost simultaneously with the actuating of the brake mechanism, the tone arm carrying the needle will be automatically raised from contact with the record and held in raised position, ready to be automatically lowered to resume the reproduction of the next selection or part of the record when the cycle of operations is repeated.

A practical application of my invention may consist of operatively connecting the device with time-controlled mechanism which may, for example, put the device into operation hourly and be used with a sound record carrying certain matter, parts of which are fitting to be reproduced successively at hourly or other intervals of time.

It will be understood that the records to be used with my device will be especially prepared for particular purposes and that the matter to be reproduced at one time will be slightly spaced from the matter on the same record to be subsequently reproduced.

The device embodies means such as a spring motor or electric motor for actuating the turn table; mechanism driven by the turn table and operatively connected with means for automatically placing the needle in operative relation to the record after the turn table has gained momentum; means for latching the needle support in operative position; means adjustable according to the matter on the record, and actuated by the needle, to automatically actuate means for closing an electric circuit, whereby a solenoid is energized and instantly actuates means connected with a brake mechanism for stopping the rotation of the turn table and also actuates the means for unlatching the needle support and for automatically raising the needle from contact with the record.

In the drawings:

Figure 1 is a top plan view of a talking machine embodying my invention, showing the parts when first placed in operative position.

Figure 2 is a side elevation of part of the mechanism shown in Figure 1, also in operative position, showing more particularly the make and break mechanism and the mechanism for raising and lowering the tone arm support. It also shows the means for applying a brake to the turn table.

Figure 3 is similar to Figure 2, but shows the parts in stationary or inoperative position.

Figure 4 is a vertical sectional view of a detail taken on the line 4—4 of Figure 3.

Figure 5 is a vertical section of said detail taken on the line 5—5 of Figure 2.

Figure 6 is a vertical section taken on the line 6—6 of Figure 1, looking in direction indicated by arrows.

Figure 6^a is a sectional view showing the brake mechanism, taken on the line 6^a—6^a of Figure 6.

Figure 7 is a horizontal section taken on the line 7—7 of Figure 6, looking downwardly, and showing more particularly the mechanism for releasing the vertical rod by which the tone arm support is held in raised or lowered position.

Figure 8 is a fragmentary plan view, en-

larged, showing the stop bar and bracket support for the tone arm, said arm being partially broken away, and part of the mechanism of Figure 1 being left out.

Figure 9 is a vertical sectional view taken 5 on the line 9—9 of Figure 8.

Figure 10 is a plan view enlarged, and broken away, of the governor mechanism for controlling the operation of the means for lowering the tone arm support, three positions of the parts being indicated.

Figure 11 is a vertical section taken on the line 11—11 of Figure 10, looking in the direction indicated by the arrows.

I have said that Figure 2 shows the operative positions of the parts and this is true except that the switch lever, (designated 88) shown in the lowered, contacting position, is in said position for only a moment during 15 the operation. The rest of the time the switch is open, as shown in Figure 3.

In that embodiment of my invention shown in the drawings, 20 is a support which may be the usual table used to rotatably support 25 a turn table 21. An electric motor 22 is located below the support 20, and is operatively connected to the turn table 21 to rotate the same. A record 23 is supported upon the turn table 21 to rotate therewith. The 30 usual tone arm or reproducer 24 carries a needle 25. The tone arm, of course, communicates with the usual sound conduit or horn, not shown.

A U-shaped frame indicated as a whole 35 at 26 is located above and rigidly secured to the table 20. The frame has downwardly extending portions 27 and 28, to which is secured a rod 29. Pivotedly connected at 30, to the shaft 29, is a supplemental frame comprising a curved bar 31 and arms 32 40 and 33. An adjustable member 34 is connected to the tone arm 24 and rests upon the curved bar 31 of the supplemental frame, to support the tone arm upon said frame when at rest in raised position. When the needle 45 is in operation, the frame bar 31 is out of contact with the attachment 34.

The supplemental frame arm 33 rests upon the upper end of a vertically movable rod 35, notched at 36. The lower end of this rod 35 engages a control bar 37 having a raised, inclined surface 38 at one end. The vertical rod 35 is raised by this wedge-like or cam surface 38 when the control bar 37 is pulled to 50 one side, that is toward the top in Figure 1, by the action of the spring 39 wrapped about the stud 40, connected to said bar 37 and to the table 20, and said vertical rod 35 is lowered when the control bar 37 is pushed in 55 the other direction, that is, toward the bottom of Figure 1, to remove the wedge or cam surface 38 from beneath the rod 35.

The bar 37 is moved in one direction, by what may be called the governor mechanism; 60 that is, mechanism driven from the turn table

21 and operatively connected to the means just described for automatically lowering the needle into operative relation to the record. The purpose of this governor is to delay the placing of the needle into operative position until the turn table 21 has gained proper momentum.

The governor comprises a drivewheel 41 which, in Figure 1, is shown in contact with the turn table 21. Said drive wheel meshes with a pinion 42 on shaft 43, said pinion 42 meshing with the spur gear 44 on shaft 45. The spur gear 44 has fixedly secured to it a cam 46 which engages a roller 47 connected to a bar 48, slotted at 49, the side margins of the slot engaging the shaft 45. The slotted bar 48 is provided with a cam surface 50 at one end, the cam 50 being adapted to engage a roller 51 on one end of an elongated arm 52 pivotally mounted at 53 to the table 20. The other end of the arm 52 engages and actuates the control bar 37 by which the vertical rod 35 is lowered and raised.

In the operation of this part of the mechanism, the turn table 21 drives the wheel 41 in the direction indicated in Figure 10. Said wheel through the pinion 43 drives the spur gear 44 to which the cam 46 is attached. The cam 46 at the beginning of the operation will have its concentric surface, indicated at 46', in engagement with the roller 47 on the slotted bar 48. This is shown in one of the dotted line positions of Figure 10, namely, that toward the left. After the cam has almost made a complete rotation, the parts will be in the position shown in full lines in Figure 10, the turn table will have gained momentum, and the slotted bar 48 will have been moved outwardly by the cam 46, to second position, where it actuates the pivoted bar 52, which pushes the control bar 37, allowing the tone arm and needle to drop; then, under the influence of the coiled spring 54, connected to the cam 50 and stationary frame 55, the slotted bar 48 will assume the third, or other dotted line position nearer the right of Figure 10, so as to bring said slotted bar 48 into contact with the pivoted lever 56. The end 56' functions as a brake against the drive wheel 41 and pushes said wheel from engagement with the turn table 21. This pivoted brake lever 56 is connected to the fixed frame 55, whereas the rest of the governor mechanism and the frame 57 to which it is connected have a slight pivotal movement about the pivot 58, for the purpose of allowing the brake 56' to push the governor mechanism, including the drive wheel, from engagement with the turn table 21. After the governor parts have been thus actuated to third position, the turn table is free to rotate until other brake means is applied, as will be explained, after a predetermined part of the record has been played.

When the vertical rod 35 has been lowered 130

by the actuating of the control bar 37, whereby the needle 25 is brought into operative relation to the record 23, said vertical rod 35 is latched in its lowered position by the following means: A dog 59 is pivotally connected at 60 to a housing or support 61, and said dog 59 is pressed by a spring 62 against a vertical rod 35, so that when in the downward movement of the rod 35 the notch 36 comes opposite the dog 59, the lever engages the notch surface and holds the rod 35 in its lowered position as shown in Figure 2.

The foregoing describes the operative positions of the parts when the record is being played, the governor mechanism having already functioned, and the control bar 37 having been moved so that its cam or wedge surface 38 has been pushed outwardly away from the vertical rod 35, thereby permitting the tone arm support 31 to drop and place the needle 25 into operative relation to the record, in which position said vertical rod 35 is latched by the dog 59 engaging the notch 36.

It will now be in order to describe the means for automatically stopping the playing of the record when the end of that part intended to be played has been reached. Referring more particularly to Figures 8 and 9, it will be seen that at one side of the pivoted arm 32 of the tone arm support, there is a second arm 63 which extends forwardly and slightly downwardly from the rod 29. There is secured to this arm 63 a flat spring 64. The arm 63 is held in adjusted position by a plunger 65 extending through a bracket 66 rigidly secured to the support 28, and spring-pressed at 67 to hold the end of the plunger 65 in an aperture in the arm 63. The end of the arm 63 is slit horizontally, near the point indicated at 68.

A stop bar 69, carrying adjustably located stop devices 70 having needle engaging points 71, has one of its ends inserted in the slot 68 of the arm 63 so as to be slidably held therein by a latch 72 pivotally mounted at 73 on the arm 63. The stop bar 69 will be so placed in the slot 68 of the arm 63 that the enlarged end 74 of said stop bar will be between the arm 63 and the flat spring 64 and capable of exercising pressure against said spring 64 when the bar is moved toward said spring.

The other end of the stop bar 69 rests upon a horizontal part of a fixed support 75 and extends through a slot 76 in the vertical portion of said support 75. The end 77 of the stop bar 69 normally protrudes beyond the wall 75 to a very slight degree, as best shown in Figure 4. The bar 69 is held in this position by the pressure of the spring 64 against the opposite end 74 of said bar 69.

The stop devices 70 are adjustably located on the bar 69 according to the matter contained on the record 23; that is to say, each

stop 70 is so placed that the point 71 will contact with the needle 25 when the end of a certain selection or part of the record is reached. When the machine is in operation, the needle 25, in its travel over part of the record, comes into contact with one of the stop points 71 and thereby moves the stop bar 69 slightly to one side (toward what appears to be the top of Figure 8) against the tension of the spring 64, whereby the end 77 of the stop bar is withdrawn from the position shown in Figure 4 and assumes that shown in Figure 5.

The effect of this slight movement of the stop bar 69 will now be described: Mounted on top of a raised platform 78, rigidly secured to the turn table 20, is a support 79, having a pair of apertured ears 80. The support 79 carries a solenoid 81. An armature 82 is pivotally connected to the ears 80 by a pin 83. The armature 82 may be provided with a handle 84 or may be connected to time-controlled mechanism for automatically lifting said armature 82.

The solenoid 81 is connected to a source of electrical power by a current wire 85 and to a contact plate or switch button 86 on the platform 78 by the wire 87. A switch lever 88 is pivotally mounted at 89 to the support 75, which is fixed to the part 78, its downwardly extending lug 90 normally resting upon the end 77 of the stop bar 69. The switch lever 88 has pivotally connected to it between its ends a slotted link 91, said link being movably connected to a part of the tone arm supporting frame 33 by a bolt 92 extending through the slotted link 91. This slotted connection permits the tone arm support to be raised and lowered without affecting the position of the switch lever 88 while the latter is being held up by its part 90 resting upon the end 77 of the stop bar 69, as shown in Figure 3.

When the stop bar 69 is moved by contact of the needle with one of the stop points 71, the end 77 of the stop bar 69 is withdrawn from beneath the lug 90 of the switch lever 88, and said lever 88 drops to the position shown in Figure 2 (and in detail in Figure 5), closing the electric circuit by contacting with the switch button 86. The switch lever 88 is brought into the electric circuit by means of the wire 93 connected to the support 75.

The closing of the switch 86-88 energizes the solenoid 81 and causes it to draw the armature 82 toward it. This movement of the armature 82 from the position shown in Figure 2 to that in Figure 3 instantly accomplishes the following results: The end 94 of the pivotally mounted bracket 95, fixed to the armature, which is raised by the lowering of the armature 82, pulls upwardly a brake rod 96, connected to a toggle link 97, connected to a housing 98, rigidly secured to the platform 78. The toggle is also connected to a

brake shoe 99, which is adapted to engage the turn table 21. Therefore the actuating of the lever end 94 sets the brake 99 and stops the rotation of the record as soon as the electric circuit is closed by the dropping of the switch lever 88 upon plate 86.

Another result of the closing of the switch will be best understood by reference to Figures 3, 6 and 7: The lower end of a downwardly extending bar 100, rigidly secured to 10 said lever 94, by the lifting of said lever 94, is made to contact with the end of the horizontally disposed foot 101 of a bent tripper 102, slidably mounted under the support 61, so that the end 103 of said tripper contacts with the downwardly bent portion of the dog 59, against the tension of the spring 62, to disengage said dog from the notched vertical bar 35. The foot 101 of the tripper 102 moves 15 in a guideway 104, the bent over portions 105 on the guideway walls engaging the curved, struck-up parts 106 at the side of the tripper foot. These parts 106 act as cams in their contact with the parts 105 and cause the end 20 of foot 101 of the tripper 102 to be depressed and disengaged by the bar 100 when the tripper 102 has functioned, before the lever 94 contacts with the frame arm 33 to lift the tone arm.

30 As the lever 94 continues upwardly, it strikes the lower surface of the end of the arm 33 of the tone arm frame, and lifts it and the tone arm and needle out of operative position. The moment of lost motion before 35 the operating lever 94 contacts with the frame 33 is sufficient to release the dog 59 which engages the notch 36 in the vertical rod 35.

The releasing of the rod 35 by the tripper action just described permits the spring 39 to function to retract the control bar 37 and 40 bring the cam surface 38 thereof under the rod 35 with the result that said rod is quickly moved upwardly toward the tone arm support and maintains it in raised position. The 45 retracting of the control bar 37 also actuates the pivoted bar 52, causing the roller 51 to press against the cam end 50 of the slotted bar 48 and restore the parts of the governor mechanism to their original position. The raising 50 of the arm 33 of the tone arm support carries with it the switch lever 88 to the raised position shown in Figure 3.

The parts remain in this inoperative position with the brake 99 applied to the turn 55 table, the tone arm support raised and the needle out of operative relation to the record, the switch 86—88 opened, the tripper 102 retracted by the hook and spring 107 from engagement with the dog 59, until the parts are 60 again actuated by manually or automatically moving the armature upwardly and the lever 94 downwardly to the position shown in Figure 2.

I claim as my invention:

1. In a talking machine, including a record-

carrying turn table, means for driving same, a movable tone arm carrying a needle and a pivoted frame-support for the tone arm, the combination of governor mechanism driven by the turn table, means operatively connected to said governor mechanism for lowering the needle into operative relation to the record, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

2. In a talking machine, including a record-carrying turn table, means for driving same, a movable tone arm carrying a needle and a pivoted frame-support for the tone arm, the combination of governor mechanism driven by the turn table, means operatively connected to said governor mechanism for lowering the needle into operative relation to the record, means for maintaining the needle in its lowered position, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

3. In a talking machine, including a record-carrying turn table, means for driving same, a movable tone arm carrying a needle and a pivoted frame-support for the tone arm, the combination of governor mechanism driven by the turn table, said governor mechanism including a pivotally mounted frame carrying a rotatable wheel, a pinion, a spur gear, a cam fixed to the spur gear, a slotted bar, and a roller on the bar in position for engagement with the cam, a cam surface on the end of the slotted bar, a stationary frame, tension means between the stationary frame and the slotted bar, a brake lever fixed to the stationary frame for engagement with the rotatable wheel and the slotted bar, and an elongated pivoted bar carrying a roller for engagement with the cam surface on the end of the slotted bar, means operatively connected to said governor mechanism for lowering the needle into operative relation to the record, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

4. In a talking machine, including a record-carrying turn table, means for driving same, a movable tone arm carrying a needle and a pivoted frame-support for the tone arm, the combination of governor mechanism driven by the turn table, means operatively connect-

ed to said goveri or mechanism for lowering the needle into operative relation to the record, said last mentioned means including a movable control bar having a wedge-like 5 surface at one end, a rod vertically movable in a support, the lower end of the rod engaging said control bar and the upper end engaging the tone arm support, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

5. In a talking machine, including a record-carrying turn table, means for driving same, a movable tone arm carrying a needle and a pivoted frame-support for the tone arm, the combination of governor mechanism driven by the turn table, said governor mechanism including a pivotally mounted frame carrying a rotatable wheel, a pinion, a spur gear, a cam fixed to the spur gear, a slotted bar, and a roller on the bar in position for engagement with the cam, a cam surface on the end of the slotted bar, a stationary frame, tension means between the stationary frame and the slotted bar, a brake lever fixed to the stationary frame for engagement with the rotatable wheel and the slotted bar, and an elongated pivoted bar carrying a roller for engagement with the cam surface on the end of the slotted bar, means operatively connected to said 25 frame for engagement with the rotatable wheel and the slotted bar, and an elongated pivoted bar carrying a roller for engagement with the cam surface on the end of the slotted bar, means operatively connected to said 30 frame for engagement with the rotatable wheel and the slotted bar, and an elongated pivoted bar carrying a roller for engagement with the cam surface on the end of the slotted bar, means operatively connected to said 35 governor mechanism for lowering the needle into operative relation to the record, said last mentioned means including a movable control bar having a wedge-like surface at one end, a rod vertically movable in a support, the lower end of the rod engaging said 40 control bar and the upper end engaging the tone arm support, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

50 6. In a talking machine, including a record-carrying turn table, means for driving same, a movable tone arm carrying a needle and a pivoted frame-support for the tone arm, the combination of governor mechanism driven by the turn table, means operatively connected to said governor mechanism for lowering the needle into operative relation to the record, said last mentioned means including a movable control bar having a wedge-like 55 surface at one end, a rod vertically movable in a support, the lower end of the rod engaging said control bar and the upper end engaging the tone arm support, the vertical rod being notched, latching means for engaging the said notched rod, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

65 9. In a talking machine, including a record-carrying turn table, means for driving same,

ated by the needle, an electric circuit including a solenoid, a switch in the circuit, means actuated by the stop means for closing the switch in the circuit, and means actuated by the energizing of the solenoid for automatically restoring the parts to inoperative position.

7. In a talking machine, including a record-carrying turn table, means for driving same, a movable tone arm carrying a needle and a pivoted frame-support for the tone arm, the combination of governor mechanism driven by the turn table, said governor mechanism including a pivotally mounted frame carrying a rotatable wheel, a pinion, a spur gear, a cam fixed to the spur gear, a slotted bar, and a roller on the bar in position for engagement with the cam, a cam surface on the end of the slotted bar, a stationary frame, tension means between the stationary frame and the slotted bar, a brake lever fixed to the stationary frame for engagement with the rotatable wheel and the slotted bar, and an elongated pivoted bar carrying a roller for engagement with the cam surface on the end of the slotted bar, means operatively connected to said governor mechanism for lowering the needle into operative relation to the record, said last mentioned means including a movable control bar having a wedge-like 80 surface at one end, a rod vertically movable in a support, the lower end of the rod engaging said control bar and the upper end engaging the tone arm support, the vertical rod being notched, latching means for engaging the said notched rod, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

8. In a talking machine, including a record-carrying turn table, means for driving same, a movable tone arm carrying a needle and a pivoted frame-support for the tone arm, the combination of governor mechanism driven by the turn table, means operatively connected to said governor mechanism for lowering the needle into operative relation to the record, adjustable stop means actuated by the needle, said stop means including an elongated stop bar, adjustable stops carried thereby, said bar being movably mounted in spaced supports, and a spring bearing against one end of the bar, an electric circuit including a solenoid, a switch in the circuit, means actuated by the stop means for closing the switch in the circuit, and means actuated by the energizing of the solenoid for automatically restoring the parts to inoperative position.

9. In a talking machine, including a record-carrying turn table, means for driving same,

a movable tone arm carrying a needle and a pivoted frame-support for the tone arm, the combination of governor mechanism driven by the turn table, said governor mechanism including a pivotally mounted frame carrying a rotatable wheel, a pinion, a spur gear, a cam fixed to the spur gear, a slotted bar, and a roller on the bar in position for engagement with the cam, a cam surface on the 10 end of the slotted bar a stationary frame, tension means between the stationary frame and the slotted bar, a brake lever fixed to the stationary frame for engagement with the rotatable wheel and the slotted bar, and an 15 elongated pivoted bar carrying a roller for engagement with the cam surface on the end of the slotted bar, means operatively connected to said governor mechanism for lowering the needle into operative relation to the 20 record, said last mentioned means including a movable control bar having a wedge-like surface at one end, a rod vertically movable in a support, the lower end of the rod engaging said control bar and the upper end 25 engaging the tone arm support, the vertical rod being notched, latching means for engaging the said notched rod, adjustable stop means actuated by the needle, said stop means including an elongated stop bar, adjustable 30 stops carried thereby, said bar being movably mounted in spaced supporters, and a spring bearing against one end of the bar, an electric circuit including a solenoid, a switch in the 35 circuit, means actuated by the stop means for closing the switch in the circuit, and means actuated by the energizing of the solenoid for automatically restoring the parts to inoperative 40 position.

10. In a talking machine, including a record-carrying turn table, means for driving same, a movable tone arm carrying a needle and a pivoted frame-support for the tone arm, the combination of governor mechanism driven by the turn table, means operatively connected to said governor mechanism for lowering the needle into operative relation to the record, adjustable stop means actuated by the needle, an electric circuit including a solenoid, a switch in the circuit, 45 means actuated by the stop means for closing the switch in the circuit, including a pivoted switch lever and a fixed contact connected in the circuit, and means actuated by the energizing of the solenoid for automatically 50 restoring the parts to inoperative position.

11. In a talking machine, including a record-carrying turn table, means for driving same, a movable tone arm carrying a needle and a pivoted frame-support for the 55 tone arm, the combination of governor mechanism driven by the turn table, means operatively connected to said governor mechanism for lowering the needle into operative relation to the record, adjustable stop means actuated by the needle, an electric circuit in-

cluding a solenoid, a switch in the circuit, means actuated by the stop means for closing the switch in the circuit, and means actuated by the energizing of the solenoid for automatically restoring the parts to inoperative 70 position, said last mentioned means including a movable armature and a lever.

12. In a talking machine, including a record-carrying turn table, means for driving same, a movable tone arm carrying a needle and a pivoted frame-support for the tone arm, the combination of governor mechanism driven by the turn table, means, including a control bar, operatively connected to said governor mechanism for lowering the needle into 75 operative relation to the record, means, including a notched vertical rod, for maintaining the needle in its lowered position, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative 80 position, said last mentioned means including a movable armature, a lever, a brake for the turn table, a spring for retracting the control bar, and a tripper for unlatching the vertical rod.

13. In a talking machine, including a record-carrying turn table, means for driving same, a movable tone arm carrying a needle and a pivoted frame-support for the tone arm, the combination of governor mechanism driven by the turn table, said governor mechanism including a pivotally mounted frame carrying a rotatable wheel, a pinion, a spur gear, a cam fixed to the spur gear, a slotted bar, and a roller on the bar in position for engagement with the cam, a cam surface on the end of the slotted bar, a stationary frame, tension means between the stationary frame and the slotted bar, a brake lever fixed to the stationary frame for engagement with the rotatable wheel and the slotted bar, and an elongated pivoted bar carrying a roller for engagement with the cam surface on the end of the slotted bar, means operatively connected to said governor mechanism for lowering the needle into operative relation to the record, said last mentioned means including a movable control bar having a wedge-like surface at one end, a rod vertically movable in a support, the lower end of the rod engaging said control bar and the upper end engaging the tone arm support, the vertical rod being notched, latching means for engaging the said notched rod, adjustable stop means actuated by the needle, said stop means including an elongated stop bar, adjustable stops carried thereby, said bar being movably mounted in spaced supporters, and a spring bearing against one end of the bar, an electric circuit including a solenoid, a switch in the circuit, means actuated by the stop means for closing the switch in the 95 100 105 110 115 120 125 130

circuit, and means actuated by the energizing of the solenoid for automatically restoring the parts to inoperative position, said last mentioned means including a movable armature, a lever, a brake for the turn table, a spring for retracting the control bar, and a tripper for unlatching the vertical rod.

5 14. In a talking machine having means for automatically placing a needle into operative relation to a record mounted upon a rotatable turn table, governor mechanism actuated by the turn table and operatively connected with the means for placing the needle into operative relation to the record.

10 15. In a talking machine having means for automatically placing a needle into operative relation to a record mounted upon a rotatable turn table, governor mechanism actuated by the turn table and operatively connected with the means for placing the needle into operative relation to the record, said governor mechanism including a pivotally mounted frame carrying a rotatable wheel, a pinion, a spur gear, a cam fixed to the spur gear, a slotted bar, and a roller on the bar in position for engagement with the cam, a cam surface on the end of the slotted bar, a stationary frame, tension means between the stationary frame and the slotted bar, a brake 25 lever fixed to the stationary frame for engagement with the rotatable wheel and the slotted bar, and an elongated pivoted bar carrying a roller for engagement with the cam surface on the end of the slotted bar.

30 16. In a talking machine having means for automatically placing a needle into operative relation to a record mounted upon a rotatable turn table, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position.

35 17. In a talking machine having means for automatically placing a needle into operative relation to a record mounted upon a rotatable turn table, adjustable stop means actuated by the needle, an electric circuit including a solenoid, a switch in the circuit, means actuated by the stop means for closing the switch in the circuit, and means actuated by the energizing of the solenoid for automatically restoring the parts to inoperative position, said last mentioned means including a movable armature and a lever.

40 In testimony, that I claim the foregoing as my sole invention I affix my signature, this 26th day of July, 1928.

45 ADOLPH C. HANSEN.
